UNITED STATES PATENT OFFICE.

FREDERICK DANIEL KEEES, OF BEATRICE, NEBRASKA, ASSIGNOR TO F. D. KEEES
MANUFACTURING COMPANY, OF BEATRICE, NEBRASKA.

CALF-WEANER.

1,268,253.

Specification of Letters Patent.

Patented June 4, 1918.

Application filed May 18, 1917. Serial No. 169,537.

To all whom it may concern:

Be it known that I, FREDERICK DANIEL KEEES, a citizen of the United States, residing at Beatrice, in the county of Gage and 5 State of Nebraska, have invented a new and useful Calf-Weaner, of which the following is a specification.

The present invention appertains to calf weaners, and aims to provide a novel and 10 improved device of that character constructed chiefly of sheet metal, and capable of inexpensive manufacture, although practical and efficient in use.

It is an object of the invention to provide 15 a calf weaner, having novel means for attaching it to the septum of the calf's nose to suspend a shield or wing therefrom.

Another object of the invention is the provision of a calf weaner of the nature indicated which although simple in construction, 20 is substantial and not apt to break, or injure the animal, the device being readily applied and removed.

With the foregoing and other objects in 25 view which will appear as the description proceeds, the invention resides in the combination and arrangement of parts and in the details of construction hereinafter described and claimed, it being understood that 30 changes in the precise embodiment of the invention herein disclosed, can be made within the scope of what is claimed, without departing from the spirit of the invention.

The invention is illustrated in the accompanying drawing, wherein:—

Figure 1 is a perspective view of the improved calf weaner.

Fig. 2 is a section on the line 2—2 of Fig. 1.

Fig. 3 is a vertical section of the upper portion of the device.

Fig. 4 is a sectional detail illustrating a modification.

In carrying out the invention, there is 45 provided a shield or apron 1 embodying a plate of sheet metal or other suitable material, provided at its upper edge with a flange 2 extending at an angle therefrom to stiffen the upper portion of the plate, and said 50 flange is provided with a downturned lip 3 to further stiffen the structure.

A pair of suspending arms 4 and 5 is provided, the same having their lower terminals bearing against that side of the shield

or wing 1 from which the flange 2 projects, 55 the lower ends of the arms being fastened by rivets 6 or their equivalents to the shield at a suitable distance below the flange 2. The arms 4 and 5 project upwardly through the respective slots 7 and 8 with which the 60 flange 2 is provided, the slot 7 being relatively short, whereby to hold the arm 4 rigid with the shield and prevent the relative swinging thereof, while the slot 8 is elongated to enable the arm 5 to swing toward 65 and away from the arm 4 in applying and removing the device. That end of the slot 8 nearest the slot 7, however, forms an abutment for the arm 5 when it is swung toward the arm 4, to limit the movement of the arm 70 5. The upper free terminals of the arms are curved toward one another, as at 9, and have the T-heads 10, said arms being readily stamped from sheet metal. Hollow knobs 11 stamped from sheet metal or other suitable material embrace the T-heads 10 and are contracted behind the same, as at 12, to hold said knobs in place, said knobs being adapted to bear against the opposite sides of 75 the septum of the nose for suspending the 80 device therefrom.

As illustrated, in Fig. 4, a turned ball 11' can be fitted upon the plain end 9 of each arm, instead of using the hollow stamped knob.

In order to hold the arm 5 when abutting the inner end of the slot 8, a leaf spring or spring catch 13 has one end fastened by a rivet 14 or otherwise, to the shield or plate 1 adjacent to the flange 2 and arm 4, the 90 upper edge of the leaf spring 13 bearing against the flange 2, to prevent the spring from swinging out of proper position. The spring 13 extends along the flange 2 underneath the same across the arm 5 opposite to 95 the shield, and is provided near its free end with a shoulder 15 to snap into engagement with that edge of the arm 5 opposite to the arm 4. The free terminal of the spring 13 has a finger piece 16 extending from the shoulder 15 and curved away from the shield 1. Said shield is provided with an opening 17 behind or coinciding with the finger piece, for facilitating the releasing of the spring by moving the finger piece 16 away from the shield 1. This opening admits the finger behind the finger piece 16 100 from either side of the shield. 105

By lifting or pushing the finger piece 16 away from the shield 1, the arm 5 is released, and can be swung away from the arm 4, in applying or removing the device. 5 To apply the device, when the arms are swung apart, they are inserted into the nostrils, and are then swung toward one another to press the knobs 11 against the septum, the spring or catch 13 snapping into 10 engagement with the arm 5 to hold it in place. The flange 2 not only stiffens the upper edge portion of the shield, but also holds the arms 4 and 5 against the shield, while the lip 3 of the flange limits the movement of the leaf spring or catch 13 away 15 from the shield, thus providing a desirable and effective arrangement.

Having thus described the invention, what is claimed as new is:—

- 20 1. A weaning device embodying a shield having an upper flange, arms connected to the shield below said flange and extending upwardly therethrough, the flange having an elongated slot for one arm permitting it

to swing toward and away from the other 25 arm, and a catch carried by the shield for engaging the swingable arm when it is swung into position toward the other arm.

2. A weaning device embodying a shield having an upper flange, arms connected to 30 the shield below said flange and extending upwardly therethrough, the flange having an elongated slot for one arm permitting it to swing toward and away from the other arm, and a catch carried by the shield for 35 engaging the swingable arm when it is swung into position toward the other arm, said flange having a lip for limiting the movement of the catch away from the shield to release the swingable arm. 40

In testimony that I claim the foregoing as my own, I have hereto affixed my signature in the presence of two witnesses.

FREDERICK DANIEL KEEES.
